CUTLERY AND SCISSORS SHARPENER

Sheldon M. Rutter, Lake Forest, Ill., assignor to John C. Hockery, Kansas City, Mo., as trustee

Application August 30, 1955, Serial No. 37,711

Term of patent 14 years

(Cl. D37—1)

Fig. 1 is a perspective view of a cutlery and scissors sharpener embodying my new design;

Fig. 2 is a front elevational view of same;

Fig. 3 is a top plan view of same; and

Fig. 4 is an elevational view taken from the opposite end of Fig. 1.

I claim:

The ornamental design for a cutlery and scissors sharpener, as shown.
